UNITED STATES PATENT OFFICE.

HARLON ASHLEY CLIFFORD AND JAMES WILLARD COBB, OF GREENFIELD, MASSACHUSETTS.

ANESTHETIC-DISPENSER.

1,318,266.

Specification of Letters Patent. Patented Oct. 7, 1919.

Application filed April 8, 1918. Serial No. 227,287.

To all whom it may concern:

Be it known that we, HARLON A. CLIFFORD and JAMES W. COBB, citizens of the United States, residing at Greenfield, in the county of Franklin, State of Massachusetts, have invented a new and useful Anesthetic-Dispenser, of which the following is a specification.

This invention relates to a device for use in dispensing anesthetics, one of its objects being to provide a simple and compact structure adapted to be attached readily to the cone ordinarily placed over the face of the patient, it being possible at all times readily to determine the amount of anesthetic within the device and the amount which has been dispensed.

A further object is to provide a device of this character which may be readily controlled by the user.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:

Figure 1 is an elevation of a dispenser embodying the present improvements, a portion of a cone being shown engaged by the dispenser; and

Fig. 2 is a section on line 2—2 of Fig. 1. Referring to the figures by characters of reference 1 designates a tube preferably of glass and which is housed within a metal jacket 2, there being a longitudinal slot within the jacket through which the glass tube 1 and the contents of said tube may be seen. Graduations may be arranged along this slot to indicate the amount of anesthetic contained within the device.

Detachably engaging the ends of the jacket 1 is a shallow conical base 4 which screws onto the lower end of the jacket 2, there being a gasket 5 of any suitable material interposed in the space between the lower end of the tube 1 and the jacket 2.

A nipple 6 is extended downwardly from

the center of the base 4 and has a tapered outlet opening 7. Downwardly diverging legs 8 extend from the base and detachably connected to the lower portion of each of these legs is a clamping plate 9, there being a thumb screw 10 for adjusting the plate toward or from the legs.

A cap 11 is screwed onto the upper end of the jacket 2 and has a screw-threaded opening 12 extending through the center thereof. Extending through this opening is the threaded portion of a valve stem 13, the end of this stem being tapered as at 14 to form a needle valve extending into the nipple 6. A clamp nut 14' engages the threaded portion of the stem 13 and is adapted to bear against the head or cap 11 and a set nut 15 engages said stem and bears against the clamp nut. A knob or head 16 is provided at the upper end of the stem 13. By means of the head 16 the stem 13 can be rotated, thus to move the needle valve toward or from its seat and regulate the outflow of liquid from the device. By tightening the nuts 14' and 15, the stem 13 can be held against rotation after adjustment.

A feed opening or funnel 17 is provided in the cap or head 11 and may be closed by any suitable device provided for that purpose.

A gasket 18 is preferably interposed between the upper ends of the tube 1 and the jacket 2 and the cap 11.

In using the device the anesthetic is placed in the dispenser through the feed opening after which the funnel 17 is closed. The legs 8 are attached to the marginal portion of the cone C by means of the clamping plates 9 and the valve 16 is then opened sufficiently to allow the anesthetic to discharge at the desired speed. By watching the level of the anesthetic through the exposed portion of the glass 1 the user can accurately determine the amount of anesthetic discharged into the cone.

To facilitate handling of the device a ring 19 may be connected to the base 4 and one of the legs 8 for reception of the thumb of the operator.

What is claimed is:

1. A device for dispensing anesthetics, including a container, legs depending therefrom, means upon the legs for clamping them upon a cone, means upon the container for indicating the amount of anesthetic dis-

pensed therefrom, and a valve in the base of the container.

2. A device of the class described including an anesthetic container, legs depending therefrom and diverging along the lines of a cone, means for detachably clamping the legs to the small end of a cone, there being a transparent portion in the wall of the container for indicating the amount of anesthetic dispensed, a valve normally seated in the bottom of the container for controlling the outflow of the anesthetic, and means extending from the top of the container for operating the valve.
- 15 3. A device of the class described including an anesthetic container, legs depending therefrom, means for detachably securing the legs to a cone, there being a transparent portion in the wall of the container for indicating the amount of anesthetic dispensed, a valve normally seated in the bottom of the container for controlling the outflow of the anesthetic, and means extending from the

top of the container for operating the valve and a lock for said means. 25

4. In a device of the class described the combination with a cone, of an anesthetic container, legs diverging downwardly therefrom along straight lines, clamps upon the legs and coöperating therewith for fastening the legs to the cone, said container having a transparent portion in the wall thereof for indicating the amount of anesthetic therein, a valved opening in the bottom of the container, means at the top of the container for operating the valve, and a handle connected to the container. 30

In testimony that we claim the foregoing as our own, we have hereto affixed our signatures in the presence of two witnesses.

HARLON ASHLEY CLIFFORD.
JAMES WILLARD COBB.
